COAXIAL TRANSMISSION LINE SWITCH

Robert A. Brennan, Torrance, Calif., assignor to Hughes Aircraft Company, Culver City, Calif., a corporation of Delaware

Filed July 22, 1959, Ser. No. 829,187
2 Claims. (Cl. 333—81)

The present invention relates to microwave transmission means and more particularly to means for controlling the amount of attenuation between two sections of a coaxial transmission line.

It is frequently desirable in microwave systems when transmitting power from one portion of a system to another portion to vary the amount of power so transmitted in response to the rate at which the system is accelerating. Heretofore, it has been customary to accomplish this by employing a so-called "G" switch containing some form of inertia element responsive to acceleration that controls a relay. The relay in turn is effective to insert or withdraw a microwave shutter into or out of the transmission line. As a result, the amount of attenuation of the power in the system will be varied in accordance with the acceleration in the system. However, such arrangements form bulky appendages to the system and also necessitate an additional external power source and accordingly are not entirely satisfactory.

It is an object of the present invention to overcome the foregoing difficulties by providing improved means that are responsive to the rate at which the microwave system is accelerating and are effective to vary the amount of attenuation between different portions of the system.

More particularly, this is to be accomplished by providing a coupling device for interconnecting two sections of coaxial transmission line that includes a cylindrical outer conductor and an inner conductor. At least a portion of a center conductor is laterally movable and mechanically interconnected with a mass. Normally, the mass will be spring biased to retain the inner conductor electrically interconnected with the center conductors in the adjacent sections of the transmission line. This will thereby insure the maximum amount of coupling between the adjacent portions of the system.

However, in the event there is acceleration in excess of some predetermined amount and in a predetermined direction, the acceleration forces on the mass will overcome the forces of the spring. The mass will then move the inner conductor so that it will become electrically disconnected from the center conductors in the adjacent sections of coaxial lines. This will present a discontinuity to the flow of microwave power through the coupling device. As a result, any power passing this discontinuity will have to be propagated therethrough in a waveguide mode. Accordingly, it may be seen that by a proper selection of the dimensions of the coupling device the amount of power attenuation may be made the desired amount for the amount of acceleration present.

In the drawing, the FIGURE is a longitudinal cross-sectional view of two sections of a coaxial transmission line connected together by means of a coupling device embodying the present invention.

Referring to the drawing in more detail, the present invention is particularly adapted for use in a microwave power transmission system 10 including a first section of coaxial transmission line 12 and a second section of coaxial transmission line 14. Each of these sections 12 and 14 includes a cylindrical outer conductor 16 and 18 and an inner conductor 20 and 22. The inner conductors 20 and 22 extend axially through the conductors 16 and 18. The ends 24 and 26 of the conductors

2

terminate substantially flush with the ends of the sections 12 and 14 and are held in concentric spaced relation with the conductors 16 and 18 by any suitable means.

The ends of the two sections 12 and 14 of coaxial line are connected together by means of a coupling device 28. The present coupling device 28 includes a cylindrical outer conductor 30 that includes a threaded portion 36 and/or a threaded fitting 38. These are adapted to be attached to corresponding sections on the ends of the two sections 12 and 14 of the coaxial line.

The outer conductor 30 is hollow so as to form a cylindrical passage 40 therethrough that substantially registers with the passages in the two sections 12 and 14. Inner conductor means are provided in this passage 40 that includes two end portions 44 and 46 and a movable center portion 43. The two end portions 44 and 46 are preferably retained in fixed axial alignment with the passage 40 by means of dielectric supports 50. The outer ends of these portions 44 and 46 are positioned so as to tightly engage the ends 24 and 26 of the inner conductors 20 and 22 and be in intimate electrical contact therewith.

The inner ends 52 and 54 of the inner conductor portions are terminated in spaced relation to each other so that an additional center portion 48 will just fit therebetween. This center portion 48 is preferably mounted on a dielectric strut 56 that is slidably disposed in a pair of aligned openings 58 in opposite sides of the outer conductor 30. It may be seen that as this strut 56 moves axially through the openings 58 the center portion 48 will be moved laterally into and out of contact with the inner ends 52 and 54 of conductor portions 44 and 46. The ends 52 and 54 of the conductors are preferably stepped or otherwise tapered so as to minimize reflections. It may also be desirable to provide an alignment pin 60 that is secured to conductor 44 and projects through conductor 48 to thereby insure the center portion 48 being maintained properly aligned with respect to the end portions.

A generally cylindrical mass 62 is fitted around the exterior of the outer conductor 30 for sliding axially thereon. It is desirable for a pair of shoulders 64 and 66 to be provided on the conductor 30 so as to form stops that effectively limit the amount of axial movement of the mass 62.

The interior of the mass 62 preferably includes double cam surfaces 68 and 70 that receive the opposite ends of the strut 56. It will be seen that the double cam surfaces 68 and 70 will hold the strut 56 therebetween and positively control the lateral position of the center portion 48. It has been found desirable for one of the cam surfaces 70 to include a spring biased section such as a pivoted lever 72. This will provide sufficient lost motion to eliminate mechanical interference that might otherwise prevent a proper electrical contact being made between the ends of the various portions 44, 46 and 48 of the center conductor. A spring 74 may be provided for resiliently forcing the mass 62 axially against one of the shoulders so as to normally retain it in this position. In the present instance the spring 74 retains the mass against the shoulder 64 so that all portions 44, 46 and 48 of the inner conductor are retained in good electrical contact.

However, in the event there is axial acceleration of the system 10 in a direction of the arrow in the drawing, the mass 62 will tend to compress the spring 74 and move axially along the exterior of the conductor 30 toward the other shoulder 66. This will simultaneously move the center portion 48 laterally of the passage 40. It should be noted that the cam surfaces 68 and 70 may have any

desired profile to impart the required lateral movement to the center portion 48. However, it is desirable for both end portions of the cam surfaces 68 and 70 to be straight and substantially parallel to the axis of the coupling unit so as to form "dead areas." Thus, even though there may be small vibratory movements of the mass 62 of the center portion 48 will not subject to any lateral vibrations.

Normally, the entire microwave system 10 will be at rest and the spring 74 will resiliently retain the mass 72 against one of the shoulders 64. The opposite ends of the strut 56 will engage the end portions of the cam surfaces 68 and 70 and consequently will be forced toward the axis of the passage 40 through the center of the coupling device 28. The ends of the center portion 48 will thus be carried against the end portions 52 and 54. The combined action of the alignment pin 60 and the spring biased portion of the cam surface 70 will insure all portions 44, 46 and 48 being retained in intimate electrical contact. Any microwave power present in the system 10 will thus be free to travel from one section 12 or 14 of the coaxial transmission line to the other section 14 or 12, respectively, with virtually no discontinuity. As a result, there will be little or no loss in the amount of power flowing therethrough.

However, if the system 10 is subjected to an acceleration having a component in the direction of the arrow, the inertia of the mass 62 will cause it to slide axially along the exterior of the outer conductor and compress the spring 74. The amount of this movement of the mass 62 along the axis of the coupling device 28 will of course be a function of the amount of acceleration. After some predetermined level is reached the ends of the strut 56 will have traversed the level portion of the cam surfaces 68 and 70. At this point, any additional acceleration will cause the strut 56 to slide through the openings 58 and carry the center portion 48 laterally therewith. When this occurs the ends 52 and 54 of the various portions 44, 46 and 48 will be moved out of electrical contact so that the flow of current therethrough will be decreased. As the acceleration increases, the amount of lateral movement of portion 48 will increase until the ends of the strut 56 are riding on the other straight portions of the cam surfaces 68 and 70 and the center portion 48 is moved to the side of the passage 40. At this point there will be no direct electrical connection between the two portions 44 and 46 and a marked discontinuity will exist in the transmission path.

Under these circumstances, any microwave power that passes from one section 12 or 14 to the other will have to be propagated across the resultant discontinuity in a circular waveguide mode along the conductive surface of the passage 40. Thus the microwave power will be coupled from one coaxial section 12 or 14 into the circular waveguide section formed by passage 40 and then coupled back into the other coaxial section 14 or 12, respectively. It is of course apparent that by a proper selection of the various physical dimensions of the sections 12 and 14 and the coupling device 28, any desired amount of attenuation of the microwave power may be obtained when there is an acceleration present in the system 10.

While only a single embodiment of the invention has been illustrated and described it will be readily apparent to those skilled in the art that numerous modifications and different embodiments may be employed. For example, the inertia mass may be made responsive to accelerations in any direction and the attenuation may be made to occur during conditions of no acceleration.

What is claimed is:

1. A microwave inertia switch comprising:
  - (a) a coaxial transmission line having an outer conductor and an inner conductor, an elongated section of said inner conductor being movable in a direction transverse to the axis thereof, said outer conductor having a hole therein adjacent the movable section of said inner conductor, said movable section having stepped portions at the ends thereof engaging in an overlapping relationship correspondingly stepped ends of the remaining sections of said inner conductor, said inner conductor having a hole extending through the overlapping stepped portions at one end of said movable section;
  - (b) a dielectric pin extending through the hole in the overlapping stepped portions of said inner conductor;
  - (c) an elongated dielectric strut rigidly engaging the movable section of said inner conductor and having an end extending through the hole in said outer conductor;
  - (d) and a mass movably disposed on the exterior of said outer conductor and having an internal cam surface contacting the end of said dielectric strut extending through the hole in said outer conductor, said cam surface being contoured in a predetermined direction to cause movement of said strut in a direction transverse to the axis of said transmission line as said mass is moved in said predetermined direction.
2. A microwave inertia switch comprising:
  - (a) a coaxial transmission line having an outer conductor and an inner conductor, an elongated section of said inner conductor being movable in a direction transverse to the axis thereof, said outer conductor having a pair of holes, each disposed on diametrically opposite sides of the movable section of said inner conductor, said movable section having stepped portions at the ends thereof engaging in an overlapping relationship correspondingly stepped ends of the remaining sections of said inner conductor, said inner conductor having a hole extending through the overlapping stepped portions at one end of said movable section;
  - (b) a dielectric pin extending through the hole in the overlapping stepped portions of said inner conductor;
  - (c) an elongated dielectric strut rigidly engaging the movable section of said inner conductor and having ends extending through the holes in said outer conductor;
  - (d) a mass encircling said outer conductor and having double internal cam surfaces contacting the ends of said dielectric strut, said cam surfaces being complementally contoured in a direction along the axis of said transmission line to cause movement of said strut in a direction transverse to the axis of said transmission line as said mass is moved in a direction parallel to the axis thereof;
  - (e) and an elastic member affixed to the exterior of said transmission line and in engagement with said mass for restraining motion thereof in a direction parallel to the axis of said transmission line.
